UNITED STATES PATENT OFFICE

VINCENT G. APPLE, OF DAYTON, OHIO

POWER WASHING MACHINE

Application filed June 14, 1928. Serial No. 285,371.

My invention relates to improvements in washing machines of the oscillating type wherein a more or less cylindrically shaped tub containing the clothes and water is 5 rocked a small part of a revolution alternately in two directions about an axis of the tub to agitate the contents thereof, and one object of my invention is to provide a machine of this type wherein the tub is so mounted and 10 the rocking mechanism so constructed as to supply the most efficient agitation with the least jar or noise.

Other objects will be apparent to those skilled in the art as the invention is described 15 in detail, reference being had to the drawings wherein—

Fig. 1 is a side view of the machine.

Figs. 2, 3, 4, 5 and 6 are cross sections taken 20 thru Fig. 1 on lines 2—2, 3—3, 4—4, 5—5, and 6—6 respectively.

Fig. 7 is a plan view of the machine.

Fig. 8 is a front view of the machine.

Figs. 9 to 13 inclusive show by comparison 25 some advantages of my improved construction.

Similar numerals refer to similar parts thruout the several views.

Referring to the drawings a frame 10 is supported on castors 11 and 12. Castor 12 has extending downward thru its stem 13 a screw 14 enlarged at its lower end as at 15 and carrying a rubber tip 16 thereon. A hand wheel 17 is supplied at the upper end of screw 14 for adjustment thereof, so that 30 the castor wheel 18 may be lowered when the machine is to be moved about or raised when it is in operation, a feature of particular value in machines of the oscillating type.

A tub 19 has fastened to the ends thereof 40 spiders 20 and 21 which are secured to the tub by bolts 22 and nuts 23, more clearly shown in Fig. 5 where a tapered head 24 of bolt 22 draws a suitably formed part of the metal of tub 19 into the tapered pocket of spider 20 thus not only making a tight joint

and leaving the tub free from bolt heads projecting from the inside thereof but greatly increasing the grip which the spider has on the tub to rock it rapidly back and forth. Spiders 20 and 21 carry bearings 25 and 26 50 which are mounted free to rock on studs 27 and 28 supported in frame 10. Mounted on frame 10 and extending upwardly therefrom is a column 29 adapted to carry at its upper end a power unit and wringer which may 55 swing about said column in a horizontal plane. The power unit and wringer forms no part of my present invention and is accordingly not herein shown.

Within column 29 and extending vertically 60 from the power plant downward is a shaft 30 having bearing in said column, said shaft at its lower end being bent to form a double crank having crank pins 31 and 32 oppositely eccentric with said shaft. Mounted free 65 to rock on stud 27 is a flanged hub 33 having studs 34 extending therefrom in a direction toward the tub and studs 35 extending therefrom in a direction away from the tub. Partly surrounding studs 35 and crank pins 70 31 and 32 and having bearing thereon are half boxes 38. Coil springs 39 under tension connect one stud 35 to crank pin 31 and another stud 35 to crank pin 32 by means of hooks formed at the ends of the springs which 75 bear in grooves in half boxes 38.

Constant rotation of shaft 30 in the same direction will therefore rock the hub 33 back and forth on the stud 27 so that by connecting and disconnecting the tub from hub 33 80 it may be made to rock or allowed to remain stationary at will.

The rocking mechanism usually applied to machines of this type comprises a single crank and a rigid connecting rod connecting 85 the crank pin to a point away from the rocking center of the tub. As the bearings of such a connecting rod usually wear away very rapidly a pounding action soon results which is not only noisy but destructive. A 90

rocking mechanism built according to my invention remains substantially the same during the life of the machine. The half boxes 38 may be made of one of the several oilless bearing metals in commercial use and may be made thick enough on the wearing surface to outlast all other wearing parts of the machine without adjustment, oiling, or any other attention. The springs 39 serving as resilient connecting rods always keep the half boxes seated on the bearing portion so that no lost motion or knock may occur, and at the same time supply a smooth action to the tub because the variable resistance of the tub at different positions of its cycle is compensated for by the give and take action of said springs. A measure of safety is also provided for should the tub be somehow inadvertently stopped while the power continued springs 39 would simply extend and contract to allow a continued rotation of the crank shaft.

While I have shown and described resilient connecting rods comprising extension springs drawing half boxes toward each other, I consider as within the scope of my invention resilient connecting rods comprising compression springs forcing half boxes apart, and while as a driving means for the springs I show a shaft extending downward from the power source, having a double crank at its lower end I may employ a similar shaft extending upward from a power source placed under the machine or I may employ a horizontally disposed shaft having a double crank thereon extending either crosswise or lengthwise with the machine or a shaft lengthwise of the machine having a crank and spring at each end of the tub, and while I show as a tub control means a mechanism for disconnecting the springs from the tub to stop rocking thereof, I may employ a mechanism for disconnecting the power means from the crank shaft to accomplish the same result, and while I prefer that a power plant for separately or simultaneously driving a wringer and washer such as I show in my co-pending application Serial No. 285,369, be used my rocking mechanism may be applied when separate power units are provided for the washer and wringer, in which case the power source need not be disconnected but may be itself brought to rest.

As a means of connecting and disconnecting tub 19, from hub 33 in the instant case I provide a control handle 40 rounded and having bearing in frame 10 at 41 and 42. An eccentrically turned portion 43 has mounted thereon block 44 which is confined between two flanges 45 and 46 extending from hub 33. By turning handle 40 the eccentric 43 thru block 44 acting against flanges 45 and 46 moves hub 33 axially on stud 27 toward or away from tub 19. When hub 33 is moved toward tub 19 studs 34 and 35 enter holes

in spider 20 to rock the tub, and when hub 33 is moved away from the tub, studs 34 and 35 are withdrawn to bring the tub to rest. A flat spring 47 secured to frame 10 has a free end adapted to bear against two flattened portions 48 and 49 of handle 40 to maintain the handle in one or the other position thus to keep the tub securely connected or entirely freed. As a means of bringing and holding the tub in proper position with the opening at the top when disconnected from the power, I may employ a coil spring similar to spring 39 connecting same point on the tub to the frame, the points of connection being selected to bring the opening to the top by the action of the spring in assuming its state of least extension. As this is common practice in machines of this type it is not herein shown or claimed in combination with other features. Another feature of particular value in my improved construction resides in the contour of the tub and the position of its rocking center, a feature which I show by comparison in Figs. 9, 10, 11, 12 and 13.

Fig. 9 shows an end view of a tub such as is used in common practice, being of substantially cylindrical form and having the rocking point 50 on the axis passing through the center of the cylinder. A partition 51 within the tub extending upwardly from the bottom is the sole means of agitation for the contents thereof as it is rocked back and forth, it being obvious that were such partition removed the contents would remain stationary regardless of the rocking action of the tub as said contents would not lower its center of gravity by shifting its position. With the partition as shown a certain amount of agitation may be had.

Fig. 10 shows an end view of a more approved form of tub used in common practice being a hollow prism of elliptical cross section the rocking center being at 52 on the center of gravity as shown. Projections 53 adjacent to the opening in the top of the tub are usually added to keep the contents from splashing out when the tub is being rocked and a plate 54 is sometimes provided in the bottom of the tub against which the clothes are rubbed when passing back and forth.

Fig. 11 shows a tub made according to my improved practice being a hollow prism of elliptical cross section as in Fig. 10 but which has the rocking center 55 considerably below the center of gravity of the prism as shown. The inside of the tub is preferably formed more or less to represent a figure 8 except for the portion which must be removed at the top of the tub for access thereto. The false bottom 56 may be a removable perforated plate which assists the washing action by water being forced upwardly thru the perforations against the clothes as they are passed thereover or it may be corrugated and without perforations and securely fixed

in the tub and if properly joined to the sides it may constitute the sole bottom of the tub.

In order to more clearly show the effect of rocking a tub on a point below the gravity axis thereof I have drawn Figs. 12 and 13 which represent tubs having the form of rectangular prisms and are so shown because the center of gravity of the contents thereof is more readily determined graphically than in a tub of oval cross section. The tub 57 Fig. 12 is rocked on the axis 58 in one direction to assume the position of the broken line 59 and in the other direction to assume the position of the broken line 60. When tub 57 is exactly half filled with water the center of gravity of the body of water when the tub is level is at 61, when rocked to position 59 it is at 62 and when rocked to position 60 it is at 63. The tub 64 Fig. 13 is rocked on the axis 65 in one direction to assume the position of the broken line 66 and in the other direction to assume the position of the broken line 67. When tub 64 is exactly half filled with water the center of gravity of the body of water when the tub is level is at 65, when rocked to position 66 it is at 68 and when rocked to position 67 it is at 69. It is readily seen from Figs. 12 and 13 that while the two tubs 57 and 64 are rocked thru the same angle the center of gravity of the water in tub 64 is not only raised and lowered to a greater extent but it is also shifted to positions farther removed from each other at each cycle of operation. In addition it may be seen that in Fig. 12 when the water has for instance accumulated about gravity center 63 and the tub is suddenly rocked to position 59 the end wall 70 simply rises allowing the water to flow away from it, while in Fig. 13 when the water has accumulated about gravity center 69 and the tub is suddenly rocked to position 66 the end wall 71 not only rises but follows after the body of water giving it a push to assist the force of gravity, and then provides a lower position 68 into which the water may fall. It is therefore obvious that the water in a tub pivoted below center moves thru a greater distance and with more force than in a tub built according to common practice. When now a tub pivoted below center has an inner contour as shown in Fig. 11, a portion of the water within when being tossed rapidly back and forth follows to a great extent the inner contour of the tub first across the bottom thereof then upward at one end and is thereby turned back, and crossing near the center of the tub again lands at the bottom at the opposite end where it is again turned upward to repeat the cycle. This motion of the water within the tub commonly called a figure 8 motion greatly assists the washing action by throwing the water which is upturned at the ends of the tub downward over the clothes in a spray.

I am aware that prior to my invention washing machines have been made wherein the tub containing the water and clothes is moved in such a manner that the end wall of the tub follows after the water giving it a punch and then in turn provides a position farther removed from its starting point wherein the water may fall, and I am also aware that machines have been made wherein a portion of the water is moved to a greater or less extent thru a figure 8 cycle and I therefore do not claim this feature broadly, as my invention does not consist in the discovery of this washing principle but rather in the discovery that this principle may be brought into use with greater effect by a properly shaped tub and a rocking mechanism suitably constructed and arranged, and while my invention preferably applies to tubs of oblong cross section it may be used to advantage in connection with tubs of round or other cross section.

While I have herein shown and described one embodiment of my invention and called attention to some of the changes which I may make in the details thereof it is understood that many other changes may be made as long as they come within the scope of the following part of the specification, wherein I claim—

1. In a power washer of the oscillating type, a tub oscillation means comprising a revolvable shaft, two oppositely disposed crank pins carried thereon and driven thereby, two studs associated with the tub positioned oppositely away from the center of oscillation, bearings carried on the studs and the crank pins, and coil springs having at their ends hooks which partly encircle the bearings to connect said crank pins to said studs with said springs under resilient tension.

2. In a power washer of the oscillating type, a tub oscillating means comprising a revolvable shaft, power means for driving said shaft, two oppositely disposed crank pins carried on said shaft and driven thereby, two studs associated with the tub positioned oppositely away from the center of oscillation, bearings carried on the studs and crank pins, coil springs having at their ends hooks which partly encircle the bearings to connect said crank pins to said studs with said springs under resilient tension, and means to stop the tub from oscillation without stopping the power means from rotation.

3. In a power washer of the oscillating type, a frame, a sheet metal tub adapted to be rocked in said frame on bearings carried by spiders fastened to the ends of said tub with bolts having tapered heads, a suitably shaped portion of the sheet metal of the tub being drawn by said tapered heads into ta-

pered pockets in said spiders for reasons substantially as described.

4. In a power washer of the oscillating type, a frame, a sheet metal tub adapted to be rocked in said frame on bearings carried by spiders fastened to the ends of said tub, said ends having greater width than height and said bearings being positioned considerably below the gravity center of said ends 10 and said spiders being fastened to said ends by bolts having tapered heads by means of which a suitably shaped portion of the sheet metal of said tub is drawn into suitably shaped pockets in said spiders.
- 15 5. In a power washer of the oscillating type, a frame, a sheet metal tub adapted to be rocked in said frame on bearings carried by spiders fastened to the ends of said tub, said ends being of oblong shape having greater 20 width than height and said bearings being positioned considerably below the gravity center of said ends, and said spiders being fastened to said ends by bolts having tapered heads by means of which a suitably shaped 25 portion of the sheet metal of said tub is drawn into suitably shaped pockets in said spider and a tub oscillating means comprising a revolvable shaft, two oppositely disposed crank pins carried thereon and driven thereby and 30 resilient connecting rods under stress joining the crank pins to points on the tub oppositely away from the center of oscillation.

6. In a power washer of the oscillating type, a tub oscillating means comprising a uni-directional continuously revolving double-throw crank shaft, and resilient means maintained under continuous stress between the crank pins and supports on the tub oppositely away from its center of oscillation.

- 35 7. In a power washer of the oscillating type, a tub oscillating means comprising a two throw crank shaft adapted to be revolved continuously in one direction, a resilient member under stress connecting one crank pin to a support on the tub somewhat removed 40 from its center of oscillation, and another resilient member under stress connecting the other crank pin to a support on the tub substantially 45 equally removed from its center of oscillation and diametrically opposite the first said support.

- 50 8. In a power washer of the oscillating type, tub oscillating mechanism comprising, a two-throw crank shaft adapted to be revolved continuously in one direction, a stressed resilient member connecting one crank pin to a support on the tub away from 55 its center of oscillation, and another equally stressed resilient member connecting the other crank pin to a support on the tub opposite the first said support, the stresses in the two 60 said resilient members being such as to oppose and balance each other.

9. In a power washer of the oscillating type, tub oscillating mechanism comprising, a two-throw crank shaft adapted to be revolved continuously in one direction, two studs associated with the tub positioned oppositely away from the center of oscillation, 70 bearings on said studs and said crank pins and resilient under stress connecting the said stud bearings to the said crank pin bearings.

10. In a power washer of the oscillating type, tub oscillating mechanism comprising, a two-throw crank shaft adapted to be revolved continuously in one direction, two studs associated with the tub positioned oppositely away from the center of oscillation, 75 bearings on said studs and said crank pins and coil springs in resilient tension connecting the said crank pin bearings to the said stud bearings.

80 11. In a power washer of the oscillating type, tub oscillating mechanism comprising, a two-throw crank shaft adapted to be revolved continuously in one direction, an oscillatory hub coaxial with the center of oscillation of the tub, two studs carried by said hub positioned oppositely away from the center of oscillation, bearing members on said studs, bearing members on said crank pins, 85 resilient means connecting the stud bearing members to the crank pin bearing members and means to connect said hub and said tub 90 for simultaneous oscillation.

12. In a power washer, a frame, a tub, a spindle affixed in said frame, a bearing member surrounding said spindle and affixed to the ends of said tub, an oscillatory hub surrounding said spindle, studs in said hub oppositely away from its center of oscillation, a two-throw crank shaft adapted to be revolved continuously in one direction, resilient 100 operating means from the crank pins to the studs to oscillate said hub and means to connect said hub to said bearing member to oscillate said tub.

110 13. In a power washer, a frame, a tub, a spindle affixed in said frame, a bearing member surrounding said spindle and affixed to the end of said tub, and axially shiftable oscillatory hub surrounding said spindle, bearing engaging means on said hub, studs in said hub oppositely away from its center of oscillation, a two-throw crank shaft adapted to be revolved continuously in one direction, bearings on the studs, bearings on the crank pins, 115 resilient means connecting the crank pin bearings to the stud bearings to oscillate said hub and means to shift said hub axially into engagement with said bearing to oscillate said tub.

125 14. In a power washer, a frame, a sheet metal tub, a spindle affixed in said frame, a bearing member surrounding said journal and secured to the end of said tub, a hub adapted to be oscillated and axially shifted on said spindle, bearing engaging means on said hub, 130

studs in said hub oppositely away from its center of oscillation, a two-throw crank shaft adapted to be revolved continuously in one direction, bearing members on the studs, bearing members on the crank pins, coil springs under tension joining the crank pin bearing members to the stud bearing members to oscillate said hub, means to shift said hub axially into or out of engagement with said bearing member to oscillate or stop said hub and means to maintain said hub in its engaged or disengaged position.

In testimony whereof I hereunto set my hand.
